(57) **CLAIM**

The ornamental design for a mirror, as shown and described.

DESCRIPTION

FIG. 1 is a perspective view of a mirror showing my new design;

FIG. 2 is a front perspective view thereof; and,

FIG. 3 is a side elevational view, the opposite side being a mirror image thereof.

The views of the mirror not shown form no part of the claimed design. The broken lines depicting feet, finials on post and cross support represent environmental elements only and form no part of the claimed design.
